UNITED STATES PATENT OFFICE.

HOWARD F. EATON, OF QUINCY, MASSACHUSETTS.

AUTOMATIC SWITCH FOR RAILWAYS.

SPECIFICATION forming part of Letters Patent No. 600,278, dated March 8, 1898.

Application filed July 18, 1896. Serial No. 598,945. (No model.)

To all whom it may concern:

Be it known that I, HOWARD F. EATON, of Quincy, county of Norfolk, State of Massachusetts, have invented an Improvement in 5 Automatic Switches for Railways and the Like, of which the following description, in connection with the accompanying drawings, is a specification, like letters and numerals on the drawings representing like parts.

This invention has for its object to improve automatically-operated switch devices for railways or other apparatus, wherein are employed one or more traveling cars or bodies adapted to run in fixed or definite lines of travel—such, for instance, as the switch device illustrated in my application for Letters Patent, Serial No. 576,094, filed January 20, 1896. In the apparatus illustrated in my said application, Serial No. 576,094, as the car approaches the switch its traveling contact passes upon an insulated section of conductor, which automatically throws the motor-circuit through the switch operating or controlling magnet, so that thereafter so long as the said traveling contact is on the said section of conductor the operator by opening and closing the motor-circuit causes the switch magnet or magnets to be operated to move the switch member as desired. By such an arrangement the power of the entire current taken from the conductor by the traveling contact is made available for moving the switch member through the switch magnet or magnets. When, however, it is desired to heat and light the car by electricity taken from the traveling contact, it is common to divide the circuit leading from the traveling contact on the car, one part or branch passing through the heating and lighting devices connected directly to the return-circuit, usually the rails, the other branch being the motor passing to and under the control of the usual rheostat or controller operated by the motorman, so that while the motor-circuit may be entirely cut off and the motor stopped there is always a certain amount of current passing from the conductor through the heating and lighting circuit whenever the heating and lighting circuits are in use, and since this heating and lighting current alone would be sufficient to operate, under certain conditions, the switch, and since this heating and

lighting current is not under the normal control of the motorman, it is evident that it would be impossible to cut off the switch-circuit for proper operation of the latter, so that said switch would under such circumstances be practically uncontrollable.

The object of this invention is to provide, in connection with a switch of the class referred to, suitable means for preventing the heating and lighting currents reaching the switch operating or controlling magnets to render the latter uncontrollable and inoperative, to thus leave the said switch magnet or 65 magnets entirely under the control of the motorman for operation, if desired, precisely as described in my previous application.

In the embodiment of my invention herein illustrated I accomplish this by introducing 70 in the switch-magnet circuit a switch-controller which uniformly shunts out the circuit magnet or magnets, this circuit-controller being responsive only to the motor or other currents exceeding the heating and lighting 75 current. In other words, the heating and lighting current is not sufficient to operate this circuit-controller, but when the motorman, the traveling contact having entered upon the insulated conductor-section referred 80 to, turns on the motor-current, as in my previous application described, this circuit-controller will respond and sever the shunt referred to, throwing the switch-controlling magnet or magnets at once in the circuit with 85 the motor and thereafter controlling the same as the motor-current for proper control of the switch, said circuit-controller when the motor-current is cut off at once resuming its normal condition, shunting out the switch 90 magnet or magnets. While, therefore, it is impossible with such an arrangement for the motorman himself to cut in or out the heating or lighting circuit, yet so far as the switch magnet or magnets are concerned the effect is 95 precisely as though he could, for whenever he cuts off the motor-circuit the circuit-controller automatically cuts off from the switch magnet or magnets the heating or lighting circuit.

The above, with other features of my invention, will be more fully elaborated in the following specification, together with the accompanying drawings.

In the drawings, Figure 1, in elevation, partial section, illustrates a sufficient portion of a car, its track, and the traveling conductor to enable my invention to be understood; 5 Fig. 2, a partial view of one form of switch-operating mechanism embodying my invention; Fig. 3, a diagram illustrating one arrangement of circuits, and Fig. 4 a modification to be described.

10 Referring to the drawings, in the embodiment of my invention therein illustrated, referring particularly to Figs. 1 and 2, the car A is mounted upon usual wheels a, adapted to travel upon suitable rails a' and receiving 15 its motor-power, herein electricity, through a usual traveling contact, typified at a², arranged to travel upon the usual conductor, typified at a³, mounted in usual manner upon supporting-poles a⁴.

10 The member to be moved, hereinafter denominated the "switch" member, (shown in dotted lines at b and fulcrumed in suitable manner,) is operated from the electro switch-magnet C, Fig. 2, arranged upon a suitable 25 base c and having its armature c' mounted upon a carrier c², constituting one form of switch-actuator and shown as in the form of a bell-crank lever fulcrumed at c³ on the base referred to. A weight c⁴ acts to retract said 30 armature when the magnet is deenergized.

At its free end the actuator c² is herein shown as grooved vertically at c⁵ adjacent the electromagnet to receive one or the other of the hooked ends d' of the connections or connecting devices d² d³, jointed at their opposite ends at d⁴ to the oppositely-extended arms d⁵, fast on a vertical shaft d⁶, mounted in a suitable support and provided at its upper end with a laterally-extended arm or crank d⁷, 35 connected with and to shift the member b referred to. When the armature c' is retracted by its magnet, its actuator c² will engage one or the other of the hooks d' and will throw the crank-arm d⁷ and the member b into one or another of its extreme positions, and the direction of movement of the crank d⁷ is determined by the particular connections or connecting devices d² d³. For shifting these connecting devices, so that either may be placed 40 in position to be operated by the actuator, as may be necessary, I have arranged the sliding shifting device e upon a support e', forming a part of or secured to the base c, said shifting device being shown as slotted at e² to receive the bolts or studs e³, which secure the said shifting device in operating position, yet permit the horizontal movement described.

45 The connecting devices d² d³ are respectively provided with laterally-extended lugs or arms d¹⁰ d¹¹, back of which are arranged the upright arms of the bell-crank levers f f', fulcrumed at f² and having their horizontal arms connected by links f³ f⁴ with the vertically-movable levers f⁵ f⁶, fulcrumed to the support e' at f⁷ f⁸.

50 The free ends of the levers f⁵ f⁶ are shown as provided with pins or projections f⁹ f¹⁰,

adapted to be engaged by the gravity-weight or gravity-actuator f¹¹, fulcrumed at f¹² and provided with pins or projections f¹³ f¹⁴, between which stands the arm f¹⁵, fulcrumed at a point coincident with the fulcrum of the gravity-actuator f¹¹.

55 With the parts in the position shown in Fig. 2 of the drawings attraction of the armature 75 by energizing of the magnet will cause the carrier c² to engage the hooked end of the connecting device d³ and swing the crank d⁷ on the member b in the direction of the arrow, Fig. 2, such movement acting also by drawing back of the connection d² to cause the lug d¹⁰, through the crank f and lever f⁵, to swing the gravity-actuator f¹¹ past its dead-center, so that in dropping to its dotted position, Fig. 2, it will engage the lever f¹⁵ and 85 shift the shifting member e to shift the hooked end of the connection d² in front of the carrier c², so that at the next subsequent operation of the armature the whole will be exerted, through the connection d², to turn the 90 crank and the member b into the opposite extreme position.

60 I desire it to be understood that my invention is not to be restricted to this particular switch-operating mechanism operating as described, the same being used simply as an example to enable my invention to be understood.

65 Referring now to Fig. 3, the current from the traveling contact a² is shown as leading 100 through a conductor 25 through the usual jackknife-switch 26 to the point 27, where the line is divided, one branch 28 passing through the field of the motor M through the wheel and rail to the ground or return circuit, the 105 other branch 29 passing through the usual rheostat m under the control of the motor-man, thence by the wire 30 to and through the motor-armature, also to the ground. The lights 31 are arranged in a branch 32, grounded 110 as shown, while the heating devices 33 are arranged in another branch 34, also grounded as shown. While my invention is not to be understood as limited to this or any other particular method of wiring, yet the diagram 115 or arrangement shown suffices to illustrate that the lights and heating devices are always in circuit with the traveling contact when in use—that is, they are not in any wise disturbed by the opening and closing of the motor-circuit. Referring still to Fig. 3, h is an insulated section of conductor arranged as in my previous application referred to, and leading from this section h is a conductor 10, leading to the switch-magnet C, the return-conductor 11 leading from the said magnet to line conductor a³, as in my previous application referred to. The circuit-controller 12 is herein shown as comprising a magnet introduced in the return-conductor 11, its armature 13 being normally retracted and in contact with the fixed contact 14 in the conductor 10, the pivot of the said armature being 120 shown as connected by a wire 15 with the con-

125 130

ductor 11. The magnet 12 is so wound or constructed that it will not respond to the heating and lighting currents or either of them, but only to currents in excess thereof, 5 so that the normal condition of said magnet, when the traveling contact reaches the section, is retracted, in which case the heating and lighting current passing from the line conductor a^3 through the conductor 11 is 10 shunted across to the conductor 10, thence to the section h , and grounded without passing through the switch-magnet C, thus leaving the latter entirely deenergized notwithstanding there is a slight current passing through 15 the traveling contact. When, however, it is desired to operate the switch, the motorman turns on the motor-current, which of course passes through the traveling contact a^2 , and the magnet 12 of the circuit-controller at 20 once responds, attracting its armature, breaking the shunt 15, and causing the full motor-current to pass from the conductor a^3 through the conductor 11, switch-magnet C to throw the switch, thence by the return-conductor 10 25 to the section h , traveling contact a^2 , wheel, rail to the ground or to the return. When the motor-current is broken, the circuit-controller at once shunts out the switch-magnet until the motor-current is again turned on or 30 until the traveling contact releases the section h . In this way by constructing the circuit-controller 12 so that it responds only to motor-currents and not to less currents I am enabled to make and break the switch-magnet 35 circuit in the same manner as though there were no continuous heating, lighting, or other currents flowing through the traveling contact.

In Fig. 4 I have shown a slightly-different 40 arrangement of circuits, and referring to said figure the circuit-controller magnet 12 is arranged in a loop 16, leading from the conductor a^3 to the section h , the switch-magnet C being introduced in the ground 17, leading 45 from the conductor a^3 through the normal open contact 14 and armature 13. In this modification whenever the motor-circuit is turned on through the section h the circuit-controller 12 is energized to attract its armature and thereby cut in the ground-tap 17 and switch-magnet C. The circuit-controller 50 12, it will be noticed, is responsive to currents of a predetermined characterization only, in the present instance the predetermined characterization being a current or currents at or above a certain number of amperes.

In the previous description the magnet which controls the work performed is denominated a "switch-magnet;" but in the 60 claims I have herein referred to it as an "operating-magnet," my invention applying to it regardless of the particular work which it performs so long as it governs the work to be performed.

65 It is obvious that my invention is not limited to any particular construction of circuit-

controller so long as it is capable of fulfilling the functions herein defined.

Having described my invention, what I claim as new, and desire to secure by Letters 70 Patent, is—

1. A conductor, and a traveling contact therefor, combined with an operating-magnet and a circuit-controller establishing the circuit of said operating-magnet, said circuit- 75 controller being arranged in series circuit with said conductor-operating magnet and traveling contact and responsive to currents of a predetermined characterization only, substantially as described. 80

2. A conductor, and a traveling contact therefor, combined with an operating mechanism controlling all the movements of the switch, and normally shunted out of circuit with said conductor and traveling contact, 85 and a circuit-controller governing the shunted circuit of said operating mechanism, said circuit-controller being arranged in series circuit with said conductor-operating mechanism and traveling contact and responsive to 90 currents of a predetermined characterization only, substantially as described.

3. A conductor, a car, a traveling contact on the car coöperating with said conductor, combined with an operating-magnet and its 95 armature, the circuit-controller governing the circuit of said operating-magnet, said circuit-controller being arranged in series circuit with said operating-magnet and traveling contact and responsive to currents of a pre- 100 determined characterization only, and an operating device on and movable with said car for determining the characterization of the current, substantially as described.

4. A source of energy and a traveling contact device therefor, combined with an operating mechanism, and a controlling device governing the operation of said operating mechanism, said controlling device being arranged in operative connection with said 105 supply of energy and contact device, and responsive to energy of a predetermined characterization only, and governing said operating mechanism for all its movements with the full main current, substantially as described. 110 115

5. A conductor, a car, a traveling contact on the car, a motor also on the car and in circuit with said traveling contact, one or more branch circuits leading from said traveling contact or motor-circuit, and containing lamps 120 or other translating devices, and an operating device in and controlling the motor-circuit, combined with an operating-magnet, a circuit-controller governing the circuit of said operating-magnet, said circuit-controller 125 being responsive to changes in current of the motor-circuit and unaffected by the passage of current through said branch circuits, and governing said operating mechanism for all its movements by a current of the same pre- 130 determined characterization, substantially as described.

6. A conductor, a car, a traveling contact on the car, a motor in circuit with said contact and conductor, a branch circuit on the car and fed from said motor-circuit, a switch-operating mechanism, and means to operate said switch mechanism for all the movements of the switch by a current of the same pre-determined characterization, and without affecting the branch circuit during simultaneous passage of current through said motor-

circuit and said branch circuit, substantially as described.

In testimony whereof I have signed my name to this specification in the presence of two subscribing witnesses.

HOWARD F. EATON.
